BOX DIVIDER

Michael Davitt, Scranton, Pa.

Application November 3, 1937, Serial No. 172,545

2 Claims. (Cl. 217—23)

The invention relates to devices for dividing the interiors of boxes into cells, and the forms of construction herein disclosed are intended for use in conventional cardboard egg boxes to contain three rows of four eggs each.

The object of the invention is to provide an exceptionally simple and inexpensive divider constructed in a novel way from a single sheet of cardboard or the like.

10 With the foregoing in view, the invention resides in the novel subject matter hereinafter described and claimed, description being accomplished by reference to the accompanying drawing.

15 Fig. 1 is a plan view of the blank used in forming a divider for a box to contain three rows of four eggs each.

Fig. 2 is a perspective view of the divider in readiness for insertion into the box.

20 Fig. 3 is a top plan view of one end portion of the divider shown in Fig. 2.

Fig. 4 is a detail longitudinal sectional view on line 3—3 of Fig. 3.

Fig. 5 is a perspective view showing the divider 25 in the box.

In the construction shown, longitudinal score lines 13^a divide the sheet 12^a into longitudinal thirds, and longitudinally extending slits 14^a are formed on said score lines, said slits being uniformly spaced apart and of uniform length, the length of said slits and the spacing thereof being shown in Fig. 1.

The sheet 12^a is provided with transverse score lines extending from edge to edge thereof and 35 disposed at right angles to the longitudinal score lines 13^a. Some of these transverse score lines (15^a) are located at the ends of the slits 14^a, and the others of said transverse score lines (16^a) are disposed centrally between the ends of said slits.

40 The blank of Fig. 1 is bent upon the longitudinal score lines 13^a to provide a strip-like bottom member 17^a and two strip-like side members 17^b, the lower edges of the latter being integrally joined to the longitudinal edges of the former 45 along the score lines 13^a. The portions of the side members 17^b which are separated from the bottom member 17^a by the slits 14^a, are buckled outwardly upon the score lines 15^a and 16^a to provide transverse partition members 18^a, and the 50 corresponding portions of the bottom member 17^a are upwardly buckled on the lines 15^a and 16^a to provide additional transverse partition members 18^b.

Before the separator or divider is placed in the box 20^a, it possesses the extended bellows-like form shown in Fig. 2 but upon insertion (Fig. 5), the side members 19^a of the partition members 18^a and 18^b occupy positions in substantial contact, providing for effective two-ply partitions which not only divide the interior of the box into the required cells, but serve to well protect the eggs.

Excellent results may be obtained from the 10 exact construction herein disclosed and it is, therefore, preferably followed, but minor variations may, of course, be made within the scope of the invention as claimed.

15 I claim:

1. A box divider comprising a strip-like bottom member, and two strip-like side members, the lower longitudinal edges of said side members being integrally joined to the longitudinal edges of said bottom member only at intervals, providing 20 each member with portions integrally connected with the adjacent member, and with intervening portions free from direct connection with the adjacent member, the latter portions of the two side members being buckled laterally outwardly into substantially V-form, and the corresponding portions of the bottom member being buckled upwardly into substantially V-form, providing partitions.

2. A box divider comprising an elongated rectangular sheet having two parallel longitudinal score lines dividing the sheet into longitudinal thirds, said sheet being provided with longitudinal slits of uniform length and uniformly spaced apart along said longitudinal score lines, 30 said sheet being also provided with transverse score lines from edge to edge at right angles to said longitudinal score lines, some of said transverse score lines being disposed at the ends of said slits and the others centrally between said ends.

35 said sheet being bent along said longitudinal score lines into trough form providing a strip-like bottom member and two strip-like side members all integrally joined to each other but having portions separated from each other by said slits, these portions of said side members being buckled laterally outward on said transverse score lines and the corresponding portions of said bottom member being buckled upwardly on said transverse score lines, providing 40

45 spaced partitions.

MICHAEL DAVITT.
